Primary Examiner — Ian Simmons*Assistant Examiner* — Dana L Sipos*(74) Attorney, Agent, or Firm* — Stevens & Showalter LLP(57) **CLAIM**

The ornamental design for a self-standing container, as shown.

DESCRIPTION

FIG. 1 is a bottom plan view of a self-standing container showing my new design;

FIG. 2 is a side elevation view thereof; and,

FIG. 3 is a bottom perspective view thereof.

The broken dot-dot-dash line(s) in the drawings define the bounds of the claim and form no part thereof.
